UNITED STATES PATENT OFFICE

2,488,902

AUTOMATICALLY TIMED RIVET SETTING MACHINE

Thomas J. Doyle, Milton, Mass., assignor to Tubular Rivet and Stud Company, Quincy, Mass., a corporation of Massachusetts

Application January 18, 1947, Serial No. 722,903

3 Claims. (Cl. 218—2)

1

This invention relates to an automatically timed rivet setting machine.

The invention has for an object to provide a novel rivet setting machine capable of performing the rivet setting operation in a superior and economical manner.

A further and more specific object of the invention is to provide a novel rivet setting machine which is capable of performing the rivet setting operation independently of the operator to the end that the rivet setting operation may be performed under uniform conditions during successive cycles in the operation of the machine.

A still further object of the invention is to provide a novel rivet setting machine of the pneumatically operated type which is capable of uniformly setting successive rivets irrespective of reasonable variations in thickness of the parts being riveted and irrespective of the judgment and skill of the operator.

With these general objects in view and such others as may hereinafter appear, the invention consists in the rivet setting machine and in the various structures, arrangements and combinations of parts hereinafter described and particularly defined in the claims at the end of this specification.

In the drawings illustrating the preferred embodiment of the invention, Fig. 1 is a side elevation of a rivet setting machine embodying the present invention; Fig. 2 is a detail view in front elevation of a solenoid operated air valve forming a part of the control mechanism to be hereinafter referred to; Fig. 3 is a detail view, partly in cross section of the rivet setting elements shown in position preparatory to setting a rivet; Fig. 4 is a similar view with the parts shown in their rivet setting position; and Fig. 5 is a diagrammatic view illustrating the control mechanism embodying the present invention.

In general, the present invention contemplates a novel rivet setting machine, and particularly a machine for setting hollow rivets, which may be used with advantage in rivetting the parts of the work which are fragile in nature, such as pieces constructed in whole or in part of ceramics, plastics and the like. In its broader aspects the invention contemplates a rivet setting machine capable of operation to perform the rivet setting operation independently of the operator, to the end that successive rivetting operations may be performed under uniform conditions as to time, thus insuring satisfactory operation without loss of production. The rivet setting machine may and preferably will comprise a machine of the

pneumatically operated type, and in the preferred embodiment of the invention such a machine is preferably provided with control mechanism for controlling the operation of the machine during each cycle so that once the machine has been started upon a cycle of operation the cycle is automatically completed within a predetermined time and independently of the operator. Provision is also preferably made for adjustably varying the length of time afforded the rivet setting operation.

Referring now to the drawings, the invention has been illustrated as embodied in a rivet setting machine for setting hollow rivets and which machine is of the pneumatically operated type wherein a driver 10 is arranged to be pneumatically and vertically reciprocated, and in one position of operation, to cooperate with an anvil 12 to perform the rivet setting operation. The parts 15 of the work to be riveted are manually held in operative relation, as illustrated in Figs. 3 and 4. As herein shown, the anvil 12 may and preferably will be of the spring pin type which includes a normally extended pin 14 over which the parts 20 to be riveted are assembled, the pin 14 extending through preformed openings in the parts, as shown in Figs. 3 and 4. During the rivet setting operation the rivet 16 is urged into engagement with the pin 14 by descent of the driver to depress the pin until the latter engages a stop whereupon the pin comes to rest and, as the driver continues, the hollow end of the rivet is caused to flow outwardly by the cooperation of the aligned annular concave surfaces of the end 25 of the pin 14 and the end of the body portion 18 of the anvil. A typical piece of work to be riveted is herein illustrated as an electrical connector having a dielectric and relatively fragile base 20, a metal washer 22 on the underside thereof, and a metal terminal 24 on the upper side. The anvil 12 is supported in a standard 25 mounted in a bracket 27 attached to the machine frame.

The rivet setting machine is further provided with means for feeding rivets into operative riveting position, said means being herein shown as comprising the usual rotary supply hopper 26, which is arranged to deposit the rivets into a guide chute 28 from which they are successively released by an escapement mechanism 30 operated upon reciprocation of the driver 10 to deposit a rivet during each cycle of operation into a separable holder 32 arranged to support the rivet in alignment with the driver 10 and the work. As herein shown, the rivet setting driver 10 is mounted in a vertical guide 34 formed in

a supporting bracket 36 attached to the machine column 38 and is arranged to be reciprocated through connections from the piston 64 (Fig. 5) of a pneumatic cylinder 40. The cylinder 40 is pivotally supported at its lower end in a bracket 42 (Fig. 1) attached to the column 38 and is provided with a piston rod 44 connected to one arm 46 of a two-armed lever pivotally mounted at 48 in the supporting bracket 36. The second arm 50 of the two-armed lever is connected by a link 52 to the upper end of the driver 10. Provision is also made for effecting intermittent movement of the rotary element in the supply hopper 26 through connections from the rocking arm 46 including a link 54 connected to a pawl and ratchet mechanism indicated generally at 56 and forming a part of the usual rivet feeding mechanism for releasing successive rivets into the inclined chute 28.

As illustrated in Figs. 1 and 2 the pneumatic cylinder 40 is of the double-acting type and the operation of the piston 64 thereof is arranged to be controlled by a valve head 60 which is mounted on a bracket 62 attached to the machine column. The valve head 60 is arranged to communicate with the lower end of the cylinder by a flexible connection 63 to effect movement of the piston 64 in one direction, and a second flexible connection 66 communicating with the upper end of the cylinder is arranged to effect movement of the piston in the opposite direction, as controlled by the valve head 60. The valve head 60 may be connected to any usual source of compressed air by a flexible tube 68 and may be provided with conventional apparatus for controlling the air including an air filter 70, pressure regulator 72 and pressure indicating gauge 74 as illustrated in Figs. 1 and 5. The pneumatic cylinder 40 may and preferably will be of the type provided with cushioning means for cushioning the piston as it approaches the end of its stroke so as to effect a gradual compression and clinching of the rivet so as to prevent breakage of relatively fragile parts to be secured together by the rivet. As herein shown, the cylinder may be provided with cushion adjusting valves 78 for controlling the cushioning effect.

From the description thus far it will be observed that through the operation of the valve head 60 the piston 64 of the cylinder 40 is actuated to effect descent of the driver 10 into rivet setting engagement with the work, the descent of the driver being terminated by the resistance of the set rivet and the work, and after a predetermined length of time the driver is elevated to complete the cycle of operation. In accordance with the present invention, provision is made for automatically controlling the valve head 60 to effect elevation of the driver 10 after a predetermined length of time, after the driver 10 has started its downstroke, sufficient to assure completion of an efficient riveting operation without dependence on the skill and judgment of the operator.

As herein illustrated, the control mechanism comprises an electrical circuit which includes a solenoid 80 for operating the valve head 60 and an adjustable time delay relay indicated generally at 82 and arranged to be set to effect opening of the circuit to the solenoid after a predetermined length of time has elapsed. As shown in Figs. 2 and 5, the solenoid plunger 84 is connected by a link 85 to one end of a lever 86 pivotally mounted at 88 above the valve head,

the lever 86 also being provided with valve stems 86, 92 on opposite sides of the pivot 88 so that in operation when the lever 86 is rocked the valves may be shifted to reverse the operation of the piston 64 of the pneumatic cylinder 40. The valve lever 86 is normally urged into its upwardly rocked position, as illustrated in Fig. 5, by a spring and rod connection 94, and is arranged to be rocked downwardly when the solenoid 80 is energized.

As illustrated in Fig. 5, the circuit to the valve actuating solenoid 80 includes a main lead 96 from the main line switch 98, a cross lead 100 connected thereto, a lead 102 connected medially of its length to the lead 100 and connected at one end thereof to a contact on the relay unit 82 and having its other end connected to one side of a manually operated, normally open, momentary contact switch 104, and a lead 106 from the other side of the momentary contact switch 104 to the solenoid 80. A lead 108 from the solenoid 80 is connected to a normally closed relay switch 110 in the time delay unit 82, and a lead 112 from the relay switch 110 is connected with the other side of the main line through a contact of the relay unit 82. As above described, the spring connection 94 is arranged to maintain the valve lever 86 in its upwardly rocked position, this position corresponding to an elevated position of the driver 10. Thus, in the operation of the control mechanism, when the momentary contact switch 104 is closed by the operator and immediately released by him, the solenoid 80 is energized to cause shifting of the valve 60 and descent of the driver 10 into rivet setting engagement with the work. Provision is made for automatically controlling the return movement of the driver 10 so that the rivet setting operation may be completed in a predetermined time after the driver is thus started downwardly, and accordingly, a holding circuit is provided for continuing the circuit to the solenoid 80 after the momentary contact switch 104 is automatically opened and, as herein shown, a micro-switch 114 which is maintained in its open position by engagement of the lever 86 in its upwardly rocked position is permitted to close when the solenoid 80 is energized to rock the lever 86 downwardly to maintain the circuit to the solenoid through lead 116, switch 114, and lead 118 thus bypassing or shunting the open momentary contact switch 104.

In the illustrated embodiment of the invention provision is further made for closing a circuit 120 to the timing mechanism of the time control unit 82 upon downward rocking of the valve lever 86 and, as herein shown, a second micro-switch 122 is arranged to be closed by engagement of the lever 86 therewith when the solenoid 80 is energized and has moved lever 86 down far enough to close switch 122. The circuit 120 to the timing mechanism includes the leads 96, 100, 102, lead 124 to the micro-switch 122 and a lead 126 from the micro-switch to a terminal 128 of the timing mechanism, the circuit being completed through the timing mechanism and through a lead 130 to the main line lead 112. In the operation of the timing mechanism, as is well-known in the art, after a predetermined length of time has elapsed after the closing of the momentary switch 104, the holding circuit to the solenoid 80 is automatically opened at the relay switch 110 to deenergize the solenoid 80 and to permit the spring connection 94 to again rock the lever 86 upwardly thus

effecting shifting of the valve head 60 and elevation of the driver 10 by the air cylinder 40. As herein shown, the timing unit 82 may and preferably will be of the known type provided with a time setting adjustment knob 132 which may be set at the time desired, as indicated by the graduations of the dial 134. Such conventional timing devices usually include a condenser which is normally charged by line current to a voltage potential determined by the setting of the knob 132. That is to say, the condenser is charged to this voltage while the microswitch 122 is open. When the momentary manual switch 104 is closed, the solenoid 80 is operated and the actuating member 86 is moved downwardly to close microswitch 122. This completes a circuit to two of the terminals of the timing device 82 through the leads 126 and 124, 102, for enabling the discharge of the condenser through a resistor. After a definite time interval, during which the condenser is discharging, which time interval is determined by the charge on the condenser as set by the adjustment of the knob 132, the relay switch 110 opens. This deenergizes the solenoid 80 to allow microswitch 122 to open, and upon opening of the microswitch 122 the condenser is again charged to the voltage set by the knob 132. The timing device 82 is also such that opening of the switch 122 causes closing of the relay switch 110 to automatically re-set the timing device for the next cycle of operation.

From the above description it will be seen that the present pneumatically operated rivet setting machine is provided with control mechanism which may be adjusted to definitely determine the time of a cycle of operation of the vertically reciprocal rivet setting element independently of operator control so as to prevent elevation of the rivet setting element prior to completion of the rivet setting operation and thus assuring complete clinching of the rivet with the work and also to prevent maintenance of the rivet setting element in rivet setting engagement with the work longer than necessary thus obtaining maximum production from the machine. It will also be observed that the present control mechanism is of particular advantage in those instances where successive parts to be riveted vary slightly in thickness, the control mechanism enabling the machine to be adjusted for the maximum thickness and in this manner assuring ample time for obtaining a completely and properly set rivet in successive parts being riveted irrespective of the usual variations in thickness and without dependence on the skill and judgment of the operator.

While the preferred embodiment of the invention has been herein illustrated and described, it will be understood that the invention may be embodied in other forms within the scope of the following claims.

Having thus described the invention, what is claimed is:

1. A rivet setting machine, comprising: a driver; an anvil; means for effecting relative movement of the driver and anvil to perform a rivet setting operation; means for controlling the operation of said first-mentioned means including an actuating member; means including an element operable by the operator for effecting initial actuation of said actuating member from one position to another to start a riveting cycle; timing means automatically operable after the machine has been started upon a riveting

cycle for controlling the time interval of the setting portion of said riveting cycle; means for effecting a return of said actuating member to said one position at the end of said time interval, said timing means being constructed and arranged so that the started riveting cycle cannot be interrupted by the operator; and means for automatically restoring the machine and timing means to starting position after the completion of the riveting cycle.

2. A rivet setting machine, comprising: a driver; an anvil; fluid operated means for effecting relative movement of the driver and anvil to perform a rivet setting operation; means for controlling the operation of said fluid operated means including a valve controlling the supply and exhaust of operating fluid to and from said fluid operated means; a valve actuating member; a circuit having a normally open manually operable switch and a solenoid connected therein for effecting initial actuation of said actuating member to move said valve from one position to another to admit operating fluid into said fluid pressure operated means to start a riveting cycle upon closing of said manually operable switch; a timing relay connected in said circuit in series with said solenoid and having a normally closed switch adapted to automatically open upon the expiration of a predetermined time interval after the closing of said manually operable switch for controlling the time interval of the setting portion of said riveting cycle and for interrupting the circuit to said solenoid to deenergize said solenoid and permit said actuating member to return said valve to said one position to exhaust operating fluid from said fluid operating means at the end of said time interval, said timing relay being constructed and arranged so that the switch of said timing relay cannot be opened by the operator during the started riveting cycle to interrupt the cycle; and means for automatically restoring the machine and timing relay to starting position after the completion of the riveting cycle.

3. A rivet setting machine, comprising: a driver; an anvil; fluid operated means for effecting relative movement of the driver and anvil to perform a rivet setting operation; means for controlling the operation of said fluid operated means including a valve controlling the supply and exhaust of operating fluid to and from said fluid operated means; a valve actuating member; a circuit having a normally open manually operable switch and a solenoid connected therein for effecting initial actuation of said actuating member to move said valve from one position to another to admit operating fluid into said fluid pressure operated means to start a riveting cycle upon closing of said manually operable switch; a holding circuit for maintaining said solenoid energized after said manually operable switch automatically opens following manual closing thereof; a timing relay connected in said circuit in series with said solenoid and having a normally closed switch for completing said holding circuit, said relay switch being adapted to automatically open upon the expiration of a predetermined time interval after the closing of said manually operable switch and for controlling the time interval of the setting portion of said riveting cycle and for interrupting the circuit to said solenoid to deenergize said solenoid and permit said actuating member to return said valve to said one position to exhaust operating fluid from said fluid operated means at the end of said

time interval, said timing relay being constructed and arranged so that the switch of said timing relay cannot be opened by the operator during the started riveting cycle to interrupt the cycle; and means for automatically restoring the machine and timing relay to starting position after the completion of the riveting cycle.
